[57] CLAIM

The ornamental design for a computer cabinet, as shown and described.

DESCRIPTION

FIG. 1 is a front, left side perspective view of a computer cabinet showing my new design;
FIG. 2 is a right side elevational view, the left side being a mirror image thereof;
FIG. 3 is a top plan view thereof;
FIG. 4 is a front elevational view thereof;
FIG. 5 is a front, left side perspective view with the doors opened and various interior members in extended position;
FIG. 6 is an enlarged detailed front elevational view of the upper left corner moulding; and,
FIG. 7 is an enlarged detailed perspective view thereof. The rear of the cabinet is flat and unornamented and forms no part of the claimed design.
